REFRIGERATOR

Robert John, New York, N. Y., and Edmund R. Boots, Short Hills, N. J.; said John assignor to said Boots

Application February 8, 1933, Serial No. 655,836

8 Claims. (Cl. 62—89)

This invention relates to the art of refrigeration and has particular reference to refrigerators of the domestic type in which the temperature reduction of the food compartment is effected by mechanical means. It is well known that a domestic refrigerator is opened very frequently during the day which permits the entrance of warm air to the confines of the cabinet which considerably lowers the efficiency of the refrigerator.

An object of the invention is to provide a suitable storage place for certain articles of food which do not require extreme cold for their preservation, said secondary storage compartment being separate from the primary food compartment, and to provide separate means of access to each compartment independently of the other, whereby food may be placed in or taken from either compartment without opening the other.

More specifically our invention comprises a door having built therein the secondary compartment, aforesaid, and a secondary door operable to permit access to said compartment without opening the primary door and to provide means whereby the air of the secondary compartment may be automatically circulated.

Numerous other objects of the invention will be apparent to those skilled in the art from a reading of the following description in conjunction with the drawings attached hereto and forming a part hereof in which:

Figure 1 is a perspective view.

Figure 2 represents a fragmentary horizontal section.

Figure 3 is a vertical section of the inner door.

Figure 4 is a fragmentary elevation showing the hinge structure.

Figure 5 is an enlarged fragmentary section of the latch mechanism.

Figure 6 is a detail view thereof.

Figure 7 is a separate detail view.

Figures 8 and 9 are detail views of an attachment which may be employed for preventing the outside air from entering the refrigerator when the auxiliary door is open.

Referring now to the drawings wherein like reference characters represent corresponding parts, numeral 1 designates a cabinet of any desirable kind having an evaporator 2 at any convenient place therein. 3 is the primary door hinged, as at 4, which is formed to define an auxiliary food compartment 5 which may have shelves 6 positioned therein. This primary door 3 is adapted to receive and retain objects which do

not require extreme cold for their preservation but which do require frequent use by a housewife. The inner wall of the door which is represented by the reference numeral 7 is provided with means for permitting the circulation of cold air therethrough which means may take the form of a series of apertures 8 positioned at the top and bottom thereof and extending inwardly into the confines of the primary food compartment 9. When the primary door is closed as shown in Figure 2, the air may circulate upwardly through the door food compartment 5, and if desired, we may place apertures 10 in the food shelves 6. The primary door is provided with sealing means 11 for engaging the front wall of the refrigerator cabinet, as at 12. In order that the wall 7 of the primary door may serve as an insulator we coat the same with metallic foil or use a bright plating of any suitable metal, said foil or said metal having a high refractive power and indicated by reference numeral 13.

A supplemental door for closing the auxiliary compartment, aforesaid, is provided and is indicated generally by reference numeral 14. Both doors are hinged to the same pintle as shown in Figure 4. This supplemental door 14 is lined on the inside with insulating material such as paper or cork 15 and is provided with an intermediate sheeting of bright metallic foil 16 of high refractive power. The supplemental door also is provided with a rubber sealing strip 17 which fits into tight abutting relationship with the flange 19 of the inner primary door 7. We have provided a single latch actuating means whereby a movement in one direction will release the supplemental door 14 whereby access may be had to the food compartment in the door without necessitating the opening of the primary door which means when turned in a different direction actuates the latch for the primary door so that both the primary and secondary doors move outwardly as a unit to permit access to the main storage compartment.

The latch mechanism comprises a keeper 23 secured to the wall 12 of the cabinet. A spring pressed bolt 24 is adapted to engage the keeper to retain the primary door 3 in its closed position. This bolt 24 is adapted to be retracted by means of a rotatable shaft 25 which includes the lever arm 26 engaging in a notch in the bolt. The shaft is provided with a notch 27 in its periphery which is adapted to be engaged by a pawl 28 to prevent rotation of the shaft in one direction from its normal position with the pawl in engagement with the notch. The extremity of the

shaft 25 is provided with a rapid pitch thread 29 which engages a similarly pitched internal thread on the handle shaft 30. The handle 30 is connected to the supplemental door 14 so that it 5 may rotate with respect to this door.

With both doors in their closed positions the threaded connection between the shaft 25 and the handle 30 retains the supplemental door 14 in its closed position. The bolt 24 retains the 10 primary door in its closed position. To open the supplemental door, the handle 30 is rotated to the right or clockwise to disconnect the threaded joint between the handle and the shaft 25. When the handle 30 is rotated clockwise the 15 pawl 28 engaging the notch 27 prevents clockwise rotation of the shaft 25. With the handle 30 and shaft 25 connected, the bolt 24 may be retracted by rotation of the handle 30 in a counter-clockwise direction.

It is obvious that the space between the inner 20 wall of the primary door and the supplemental door 14, aforesaid, is of sufficient depth to accommodate bottles of milk, packages of butter, bacon and the like and that the holes or apertures 8, herein referred to, are sufficient to permit cold air, set up by the evaporator, to enter the compartment within the door at the top thereof to displace warmer air downwardly and outwardly in the main food compartment of the 25 refrigerator. There is thus a circulation of air taking place in the main compartment and a separate circulation of air taking place in the door compartment. By our invention the supplemental door may be opened frequently without causing an influx of warm air from the outside 30 which necessitates an increase of refrigerative energy in order to subtract heat from the food compartment to a desirable degree. We have observed that the insertion and removal of many 35 small articles frequently stored in a refrigerator, such as butter, milk, eggs, bacon, etc., bring about, by far, the greatest percentage of door openings. Such articles do not require extreme cold for their preservation and it is proposed under our invention to store them in the intra-mural space of our improved door. Such articles may be inserted and removed without opening the complete double door of the refrigerator 40 whereby the energy required to keep the main food compartment at the desirable temperature is materially lessened; further such articles as are stored in said intra-mural space are conveniently displayed on their shelves, in full sight when the outer door is opened thereby, adding 45 to the convenience of the refrigerator from the users' standpoint. Further by providing insulating means as described we actually increase the storage space of a refrigerator equipped with our improved door without reducing the effectiveness 50 of the insulation.

Further it will be understood that instead of using apertures 8 in the shell of the primary door, slots or other forms of communication may be provided for permitting the circulation of cold 55 air into the door compartment from the main cabinet compartment. Moreover, if desired, means may be provided for closing off the apertures to prevent circulation of air through the compartment formed in the main door when the 60 secondary door is opened thereby to prevent warm air from rushing into the door compartment and from thence into the refrigerator cabinet. Such means are roughly illustrated in Figures 8 and 65 9 and comprise shutter coverings 26 mounted on 70 the main door and adapted to close the apertures 75

21 when the supplemental door 14 is opened independently of the main door. A spring may be provided for normally urging the shutters into their closed positions as shown in Figure 9. When, however, the supplemental door is closed, as shown in Figure 8, the same engages the finger 22 and swings the hinge shutter 26 to the position shown in Figure 8 whereby air is permitted to circulate in the manner above described. 10

Various changes may be made without departing from the spirit of our invention. For instance, a glass door may be employed with an air space between two complete glass sheets. The glass sheets may be in the form of laminated structures with intervening reinforcing sheets. The structure of the supporting means for the food articles in the door compartment may also be varied. Thus, wire mesh shells extending, for instance, about two-thirds of the way across the door and in staggered relation may be employed to take care of ventilation. Thus it would allow for the shelf means to extend the full depth of the door, which is quite desirable. Our claims, therefore, are not restricted to the details of construction as we are well aware of the fact that the basic conception herein disclosed and claimed may be physically expressed in various structural environments. 15 20 25

We claim:

1. A domestic refrigerator comprising a cabinet having a front opening formed therein and a door hinged to the cabinet for closing said opening, said door having an inner wall located within said cabinet and outwardly extending end walls defining an open-faced auxiliary food compartment, means for cooling said compartment and panel means for closing the same from the outside, said last-named means being hingedly supported and common latching mechanism adapted 30 to release either the panel or the door. 35

2. In a refrigerator, a cabinet having a back and side walls with an opening in the front wall, a door hinged to the cabinet for closing said opening, said door being shaped to provide an auxiliary food compartment and extending substantially into the cabinet through said opening, a panel adapted to be opened from the outside to expose said auxiliary food compartment, said panel and door being hinged on a common axis 45 50 and latching means permitting either the panel or the panel and door to be opened.

3. A domestic refrigerator comprising a cabinet provided with cold-producing means situated therein, which causes a circulation of air therein, a movable door, an auxiliary food compartment associated therewith, and latching means operable to permit the door to be opened without disturbing the fixed relationship of the auxiliary food compartment relative to the cabinet or operable to permit the door and the auxiliary food compartment to simultaneously move when access to the cabinet is desired. 55 60

4. A domestic refrigerator comprising a cabinet provided with cold-producing means situated therein which causes a circulation of air therein, a movable door, an auxiliary food compartment associated therewith, so constructed and arranged as to be affected by the circulation of air within the cabinet, control instrumentalities operable from the outside of the door for fixedly securing the auxiliary food compartment to the cabinet whereby the door may be opened to permit access to the food compartment from the outside of the cabinet, said control instrumentalities 65 70 75

- being also operable to release the fixed position of the auxiliary food compartment with respect to the cabinet whereby the door and auxiliary food compartment may be both moved when access to the interior of the cabinet is desired.
5. A domestic refrigerator comprising a cabinet provided with cold-producing means for causing a circulation of air therein, said cabinet having an opening in one of its walls and a movable door for said opening, an auxiliary food compartment associated with the door, securing means for maintaining the auxiliary food compartment in a fixed position relative to the cabinet when the door is opened whereby access to the food compartment can be obtained from the outside of the cabinet without necessitating exposure of the cabinet to the outside atmosphere when the auxiliary food compartment is being utilized, and means for permitting simultaneous opening 10 movement of the door and auxiliary food compartment associated therewith when access to the interior of the cabinet is desired.
6. A domestic refrigerator comprising a cabinet provided with cold-producing means situated therein which causes a circulation of air therein, a movable door, an auxiliary food compartment associated therewith, latching means for securing the auxiliary food compartment in fixed relation with respect to the cabinet whereby the door may be opened to expose the auxiliary food compartment without disturbing its closed position, said latching means being operable to release the auxiliary food compartment and to permit it to be opened when access to the cabinet is desired.
7. In a refrigerator, the combination, with a casing having a cooling compartment and provided with an opening in one wall forming the entrance to said compartment, of an auxiliary compartment structure swingingly mounted for movement into or out of said opening, said structure comprising a frame defining a cooling space normally in communication with said compartment, an outer door movable with respect to said frame, pivoted closure means movable into one position to establish such communication and into another position to interrupt the same, means urging the closure means to the second named position and means operated by the closing of said door for moving the closure means to 15 the first position.
8. In a refrigerator, the combination, with a casing having a cooling compartment and provided with an opening in one wall forming the entrance to said compartment, of an auxiliary 20 compartment structure swingingly mounted for movement into or out of said opening, said structure comprising a frame defining a cooling space normally in communication with said compartment, an outer door movable with respect to said frame, pivoted closure means movable into one position to establish such communication and into another position to interrupt the same, and means operated by the closing of said door for 25 moving the closure means to the first position.
